COMBINED MAILBOX AND SUPPORT THEREFOR

Frank Joseph Herblan, 42 Shoshone St., Denver, Colo.

Filed May 15, 1959, Ser. No. 55,921

Term of patent 3½ years

(Cl. D74—9)

FIG. 1 is a front perspective view of a combined mailbox and support showing my new design;

FIG. 2 is a rear perspective view thereof;

FIG. 3 is a left side elevational view with a portion of the support being shown broken away for convenience of illustration;

FIG. 4 is a front elevational view thereof; and

FIG. 5 is a top plan view thereof.

I claim:

The ornamental design for a combined mailbox and support therefor, as shown and described.
